(57) **CLAIM**

The ornamental design for a water generator unit, as shown and described.

DESCRIPTION

FIG. 1 illustrates a front-left side perspective view of the water generator unit showing our new design;

FIG. 2 illustrates a back-left side perspective view thereof;

FIG. 3 illustrates a front elevational view thereof;

FIG. 4 illustrates a rear elevational view thereof;

FIG. 5 illustrates a left side elevational view thereof;

FIG. 6 illustrates a right side elevational view thereof;

FIG. 7 illustrates a top plan view thereof; and,

FIG. 8 illustrates a bottom plan view thereof.

The broken lines in the drawings illustrate portions of the water generator unit which form no part of the claimed design.
